UNITED STATES PATENT OFFICE

146,580

DESIGN FOR A TOY AIRPLANE

Jerome J. Miller, Ottoville, Ohio

Application July 31, 1945, Serial No. 121,104

Term of patent 14 years

(Cl. D34—15)

To all whom it may concern:

Be it known that I, Jerome J. Miller, a citizen of the United States, residing at Ottoville, in the county of Putnam and State of Ohio, have invented a new, original, and ornamental Design for a Toy Airplane, of which the following is a specification, reference being had to the accompanying drawing, forming a part thereof.

Figure 1 is a bottom plan view of an element for rotating the propeller of a toy airplane, embodying my new design.

Figure 2 is a side elevational view thereof, and

Figure 3 is a vertical, transverse section through the device as seen on the line 3—3 of Figure 2.

The characteristic feature of my design resides in the serrations arranged on the fuselage of a toy airplane, as shown.

I claim:

The ornamental design for a toy airplane, as shown and described.

JEROME J. MILLER.
